UNITED STATES PATENT OFFICE.

JOHN H. ABBOTT, OF FREDERICK CITY, MARYLAND.

CIGAR-KNIFE.

Specification forming part of Letters Patent No. 43,823, dated August 16, 1864.

To all whom it may concern:

Be it known that I, JOHN H. ABBOTT, of Frederick City, in the county of Frederick and State of Maryland, have invented a new machine for cutting off the "lighting" ends of cigars during the process of their manufacture, and for gaging the length of the same; and I do hereby declare the following to be a true and exact description thereof, reference being had to the accompanying drawings and letters of reference marked thereon, forming a part of this my specification.

To enable others skilled in the art to make and use my invention, I will proceed to describe the same with reference to the drawings, in which—

Figure 1 is a perspective view of my machine for cutting off the lighting ends of cigars in the process of their manufacture, and for gaging the length of the cigar; Fig. 2, a side elevation, and Fig. 3 a section, of the knives in the act of making a cut.

In the process of manufacturing cigars it is of importance to have every cigar of the same length which belongs to the same "lot" being made, and that their lighting ends should be cut perfectly square off, or at right angles with the length of the cigar. Lack of workmanship in these particulars greatly detracts from the beauty of finish of the article, as well as the chances of sale after manufacture. As ordinarily practiced, a hand-knife is used to cut the ends, which knife is grasped by the right hand of the operator after the length of the cigar is determined. The length is ordinarily signified in this way: The operator, after finishing the "lip end," places such end even with a mark upon the "roll-board," and with his left hand covering the whole cigar depresses his wrist-joint or rear portion of his hand upon that part of the cigar to be cut, thereby pressing the cigar over the edge of the roll-board, and if the pressure be sufficient the edge of the roll-board will leave a crease across the cigar, which serves as a guide for the cut; but this operation, aside from the time required to gage the cut and the usual lack of accuracy in making the cut itself by the use of a common hand-knife, also flattens the cigar to such extent as to require a rerolling after its end is cut off, in order to secure a handsome finish; and, besides this, the pressure constantly re-

peated upon or near the wrist-joint of the operator has a constant tendency to lame his arm. By my machine these objections are overcome, extra manipulation is saved, and greater beauty of finish of the cigar is effected.

In the drawings, A indicates the gage-board for the length of the cigar, and which at the same times serves as a foundation for the machine. At one of its sides, as at b, a stationary knife is securely affixed, to which a vibrating knife, b', is hinged, as indicated at c. A curved arm, d, attached to the stationary knife b, as represented, supports at its upper end a coil-spring, E, one end of which is secured to the arm d and the other to the vibrating knife-blade b', the tension of the said spring being such as to cause the knife automatically to assume its position as shown in Fig. 2 when not pressed by the hand of the operator. The knives b b' both have cutting-edges, as indicated in Fig. 3, and to prevent the undue expansion of the spring, as well as to indicate the completion of the cut, I provide a metallic detent, f, applied to the gage-board A, as clearly represented in Fig. 1. The stationary knife b is so applied to the gage-board that its cutting-edge shall be above the face of the detent f, and so far above that when that portion of the vibrating knife, as at x, shall strike against the face of the detent the end of the cigar will be cut off. Thus in rapid working the striking of the two parts together will indicate the completion of the cut.

In dark outlines in Fig. 1 I have shown a cigar which is desired to be of a length equal to the width of the gage-board. In this position the cigar will be laid after the operator has finished its lip end, the cigar being held in the left hand, and the end, as at g, registering with the rear side of the gage-board, while its opposite end rests upon the stationary knife b. If a cigar of greater length than the width of the gage-board is desired, as represented in red outline, then in such case the extra length may be gaged by having the lip end of the cigar project, as at g', over the gage-board the width of one or more fingers of the operator, the finger being held against the rear side of the gage-board and upon the end g' in such manner as to make the finger just cover the extra length desired; or the gage-board A may be made to constitute the roll-board, in which

case its dimensions should be about twelve inches square, under which circumstances the length of the cigar may be gaged by slips of paper pasted upon the board at proper distances from the knives as a mark for the finished end *g* of the cigar.

It is obvious that an adjustable bar for gaging the length of the cigars may be screwed on the opposite edge of the bed *A* to that on which the knife is placed. This, however, is optional with the user. When the cigars are thus placed, the handle *h* is depressed and the cut effected, whereupon, the hand of the operator being re-

moved from the handle, the vibrating knife automatically resumes its position as shown in Fig. 2, ready for another cut.

What I claim as new, and desire to secure by Letters Patent of the United States, is—

A machine for gaging the length and cutting off the ends of cigars in the process of their manufacture, constructed and operating substantially as described.
